CLAIM

The ornamental design for a pelvic muscle exercise machine, as shown and described.

DESCRIPTION

FIG. 1 is a perspective view of a first embodiment of a pelvic muscle exercise machine.
 FIG. 2 is a top view of the pelvic muscle exercise machine of FIG. 1.
 FIG. 3 is a bottom view of the pelvic muscle exercise machine of FIG. 1.
 FIG. 4 is a left side view of the pelvic muscle exercise machine of FIG. 1.
 FIG. 5 is a right side view of the pelvic muscle exercise machine of FIG. 1.
 FIG. 6 is a rear view of the pelvic muscle exercise machine of FIG. 1, shown in a closed position.
 FIG. 7 is a front view of the pelvic muscle exercise machine of FIG. 1, shown in a closed position.

FIG. 8 is a perspective view of an upper arm of the pelvic muscle exercise machine of FIG. 1.
 FIG. 9 is a top view of the upper arm of the pelvic muscle exercise machine of FIG. 1.

FIG. 10 is a bottom view of the upper arm of the pelvic muscle exercise machine of FIG. 1.
 FIG. 11 is a left side view of the upper arm of the pelvic muscle exercise machine of FIG. 1.

FIG. 12 is a right side view of the upper arm of pelvic muscle exercise machine of FIG. 1.
 FIG. 13 is a rear view of the upper arm of pelvic muscle exercise machine of FIG. 1.

FIG. 14 is a front view of the upper arm of pelvic muscle exercise machine of FIG. 1.
 FIG. 15 is a perspective view of a lower arm of the pelvic muscle exercise machine of FIG. 1.

FIG. 16 is a top view of the lower arm of the pelvic muscle exercise machine of FIG. 1.
 FIG. 17 is a bottom view of the lower arm of the pelvic muscle exercise machine of FIG. 1.

FIG. 18 is a left side view of the lower arm of the pelvic muscle exercise machine of FIG. 1;
 FIG. 19 is a right side view of the lower arm of the pelvic muscle exercise machine of FIG. 1.

FIG. 20 is a rear view of the lower arm of the pelvic muscle exercise machine of FIG. 1.
 FIG. 21 is a front view of the lower arm of the pelvic muscle exercise machine of FIG. 1.

FIG. 22 is a perspective view of a second embodiment of a pelvic muscle exercise machine.
 FIG. 23 is a top view of the pelvic muscle exercise machine of FIG. 22.

FIG. 24 is a bottom view of the pelvic muscle exercise machine of FIG. 22.
 FIG. 25 is a left side view of the pelvic muscle exercise machine of FIG. 22.

FIG. 26 is a right side view of the pelvic muscle exercise machine of FIG. 22.
 FIG. 27 is a rear view of the pelvic muscle exercise machine of FIG. 22, shown in a closed position.

FIG. 28 is a front view of the pelvic muscle exercise machine of FIG. 22, shown in a closed position.
 FIG. 29 is a perspective view of an upper arm of the pelvic muscle exercise machine of FIG. 22.

FIG. 30 is a top view of the upper arm of the pelvic muscle exercise machine of FIG. 22.
 FIG. 31 is a bottom view of the upper arm of the pelvic muscle exercise machine of FIG. 22.

FIG. 32 is a left side view of the upper arm of the pelvic muscle exercise machine of FIG. 22.
 FIG. 33 is a right side view of the upper arm of pelvic muscle exercise machine of FIG. 22.

FIG. 34 is a rear view of the upper arm of pelvic muscle exercise machine of FIG. 22.
 FIG. 35 is a front view of the upper arm of pelvic muscle exercise machine of FIG. 22.

FIG. 36 is a perspective view of a lower arm of the pelvic muscle exercise machine of FIG. 22.
 FIG. 37 is a top view of the lower arm of the pelvic muscle exercise machine of FIG. 22.

FIG. 38 is a bottom view of the lower arm of the pelvic muscle exercise machine of FIG. 22.
 FIG. 39 is a left side view of the lower arm of the pelvic muscle exercise machine of FIG. 22.

FIG. 40 is a right side view of the lower arm of the pelvic muscle exercise machine of FIG. 22.

FIG. 41 is a rear view of the lower arm of the pelvic muscle exercise machine of FIG. 22; and,

FIG. 42 is a front view of the lower arm of the pelvic muscle exercise machine of FIG. 22.

Broken lines in the Figures illustrate portions of the pelvic muscle exercise machine that form no part of the claimed design.
